US00D799520S

(12) **United States Design Patent** (10) Patent No.: US D799,520 S
Howard et al. (45) Date of Patent: ** Oct. 10, 2017

- (54) **DISPLAY SCREEN WITH GRAPHICAL USER INTERFACE**

(71) Applicant: **Caterpillar Inc.**, Peoria, IL (US)

(72) Inventors: **Mitchell Howard**, Lebanon, IN (US);
David Ochoa, Peoria, IL (US); **Omar Bennani**, Chicago, IL (US)

(73) Assignee: **Caterpillar Inc.**, Peoria, IL (US)

(**) Term: **15 Years**

(21) Appl. No.: **29/572,206**

(22) Filed: **Jul. 26, 2016**

(51) **LOC (10) Cl.** **14-04**

(52) **U.S. Cl.**
USPC **D14/486**

CLAIM

The ornamental design for a display screen with graphical user interface, as shown and described.

DESCRIPTION

The FIGURE is a front view of a display screen with graphical user interface showing our new design. The broken lines of uneven length show the display screen and form no part of the claimed design. The broken lines of even length shown in the drawing illustrate portions of the graphical user interface that form no part of the claimed design.

1 Claim, 1 Drawing Sheet
